(57) **CLAIM**

The ornamental design for a combined cooking device, as shown and described.

DESCRIPTION

FIG. 1 is an exploded perspective view of a combined cooking device with lid, strainer and container showing my new design;

FIG. 2 is a perspective view of the assembled cooking device of my new design;

FIG. 3 is a front elevational view of my design, the rear elevational view being a mirror image thereof;

FIG. 4 is a right side elevational view of my design, the left side elevational view being a mirror image thereof;

FIG. 5 is a top plan view of my design;

FIG. 6 is a bottom plan view of my design;

FIG. 7 is a top view of the container of my design with the lid and strainer removed;

FIG. 8 is a top plan view of the lid of my design;

FIG. 9 is a bottom plan view of the lid of my design;

FIG. 10 is a front elevational view of the strainer of my design, the rear elevational view being a mirror image thereof;

FIG. 11 is a right side elevational view of my design, the left side elevational view being a mirror image thereof;

FIG. 12 is a top view of the strainer of my design; and,

FIG. 13 is a bottom view thereof.

The broken lines shown in FIG. 1 are for illustrative purposes only.
